UNITED STATES PATENT OFFICE.

WILLIAM FRANKLIN COLLINS, OF CENTERVILLE, IOWA, ASSIGNOR OF ONE-HALF TO
JOHN J. SCHWEINEFUSS, OF CENTERVILLE, IOWA.

DESIGN FOR A PNEUMATIC TIRE.

58,180.

Specification for Design.

Patented June 21, 1921.

Application filed May 14, 1920. Serial No. 381,476. Term of patent 14 years.

To all whom it may concern:

Be it known that I, WILLIAM FRANKLIN COLLINS, a citizen of the United States, residing at Centerville, in the county of Appanoose and State of Iowa, have invented a new, original, and ornamental Design for Pneumatic Tires, of which the following is a specification, reference being had to the accompanying drawing, forming part thereof.

The figure is a perspective view of a pneumatic tire, showing my new design.

I claim:

The ornamental design for a pneumatic tire, as shown.

WILLIAM FRANKLIN COLLINS.
